DESIGN FOR A BRICK FOR WALL CONSTRUCTION

Joseph Iannone, Cleveland, Ohio

Application July 3, 1936, Serial No. 63,643

Term of patent 14 years

To all whom it may concern:

Be it known that I, Joseph Iannone, a subject of the King of Italy, residing at Cleveland, in the county of Cuyahoga and State of Ohio, have invented a new, original, and ornamental Design for a Brick for Wall Construction, of which the following is a specification, reference being had to the accompanying drawing, forming part thereof.

Figure 1 is a top plan view of a brick for wall construction, showing my new design, and Figure 2 is a perspective view of the brick.

I claim:

The ornamental design for a brick for wall construction, as shown.

JOSEPH IANNONE.
